UNITED STATES PATENT OFFICE.

JOSEPH F. PLEIN, OF PATTONVILLE, MISSOURI.

LOWERING DEVICE FOR COFFINS.

SPECIFICATION forming part of Letters Patent No. 633,902, dated September 26, 1899.

Application filed April 17, 1899. Serial No. 713,383. (No model.)

To all whom it may concern:

Be it known that I, JOSEPH F. PLEIN, a citizen of the United States, residing at Pattonville, in the county of St. Louis and State 5 of Missouri, have invented certain new and useful Improvements in Lowering Devices for Coffins; and I do hereby declare the following to be a full, clear, and exact description of the invention, such as will enable others skilled in the art to which it appertains to make and use the same.

My invention relates to improvements in lowering devices for coffins; and it consists in the novel combination and arrangement 15 of parts, as will be hereinafter more particularly described and claimed.

In the drawings, Figure 1 is a side elevation of my complete invention, showing the same as used in connection with a grave; and 20 Fig. 2 is a top plan view of the same.

The object of my invention is to construct a simple and practical frame or support which is designed to straddle the grave and a suitable mechanical device mounted upon said 25 frame which is adapted to be operated by hand from one or both sides of the frame, to which device suitable straps are attached capable of being wound and unwound, the latter or lower ends of the same adapted to 30 embrace an ordinary coffin, whereby the latter is suspended and readily and conveniently lowered into the grave without accident, the said frame being portable, whereby it is adapted to be carried to any place where it is desired to be used within the graveyard.

Referring to the drawings, 1 represents a portable frame or support which is made of suitable material and design and is adapted to straddle the grave, the lower ends of which 40 rest upon the ground on either side of the grave. Mounted upon and secured to the top of the said frame or support 1 is a lowering device 2, which is composed of two shafts 3, mounted in suitable bearings 4, one end of 45 each shaft being provided with a crank 5, which are adapted to be grasped by the hand of the operator, one or both of said cranks being operated as may be found most desirable. Secured to each shaft 3 is a reel or spool 50 6 which are substantially on a line with one another, and fastened to each of the same is one end of a strap 7, making two in number,

which are adapted to be wound and unwound upon the same, the lower ends of said straps being provided with snap-hooks 8, which are 55 adapted to snap into rings 9, located a suitable distance from the lower end of said straps and secured there-to, whereby loops 10 are formed for receiving the coffin before the latter is lowered into the grave. Also secured 60 to each of the shafts 3 of the lowering device is a gear-wheel 11, which are consequently two in number, and which mesh with one another, whereby when either or both of the shafts 3 are operated by hand from one side 65 of the frame 1 the spools 6 are simultaneously operated in their proper direction for winding and unwinding the strap 7, secured to the same.

In practice the coffin is first placed over the 70 grave and supported above the same upon a suitable skid or board such as is commonly employed, and while the coffin is in this position the loops 10, located at the lower end of the straps 7, are placed over the opposite ends 75 of the coffin and the lowering device turned in the proper direction to slightly raise the coffin in order that the skid or board may easily and readily be removed from beneath the same, after which the lowering device is 80 operated in the reverse direction, unwinding the straps 7 from the spools 6, in which operation the coffin is gradually lowered to the bottom of the grave, after which the lower ends of the straps are removed from the 85 coffin in the usual manner and the said straps wound upon the spools 6.

I do not limit myself to the precise construction and arrangement of parts herein shown and described, as the same may be changed 90 in many respects without departing from the nature of my invention, the principal object being to provide a support which is adapted to be supported upon the ground adjacent to the grave and straddling the same, a suitable lowering mechanism or reel adapted to be operated by hand, and straps or other similar devices adapted to be wound and unwound upon said reel, the lower ends of which are adapted to hold and suspend a coffin for lowering the latter into a grave.

Having fully described my invention, what I claim is—

1. A lowering device for coffins, comprising

ing a suitable frame, the lower ends of which are adapted to rest upon the ground on either side of the grave, a lowering device mounted upon said frame, and composed of two parallel shafts, cranks for each of said shafts, and arranged on opposite sides of the frame, spools secured to each of said shafts, on a line with one another, suitable straps, one end of each of which is attached to said spools, and having their opposite ends provided with detachable loops for receiving a coffin, a gear-wheel also fixed to each of said shafts, and meshing with one another, whereby the said spools are operated simultaneously, and in opposite directions, as and for the purpose described.

15. 2. In combination with a suitable lowering

device, of spools forming a part of the same, and on a line with one another, straps, one end of each of which is attached to the said spools, and adapted to be wound upon the latter, snap-hooks secured to the free ends of the same, and rings located at a suitable distance from said hooks, and also secured to one side of said straps, whereby suitable loops may be formed on the flat side of the belt, as and for the purpose described.

In testimony whereof I affix my signature in presence of two witnesses.

JOSEPH F. PLEIN.
